CIRCUIT BREAKER

William H. Frank, Detroit, Mich., assignor to
 Bulldog Electric Products Company, Detroit,
 Mich., a corporation of West Virginia

Original application March 6, 1933, Serial No.
 659,714. Divided and this application January
 9, 1936, Serial No. 58,439

11 Claims. (CL 200—116)

This application relates to circuit breakers, and is a divisional of a prior application, Serial No. 659,714, filed March 6, 1933.

In that application there is disclosed a breaker having a link 24 normally held anchored at one end by a thermal latch 14 and movable by means of a handle 42 over the center of rotation 43 of the handle for make and break action; the mechanism is such that movement of the free end 37 of the link away from a spring abutment 29 thereon determines the degree of flexure of the operating spring 27 of the breaker. In that application, an over-center arrangement of the parts is utilized and the free end 37 of the link 24 is arranged to move circularly only, around the center 43 of the handle 42.

The principal object of the present invention is to provide, in a construction generally similar to that of application Serial No. 659,714, an arrangement of parts providing a separation of link end 37 from spring abutment 29 much greater than that which is possible in the construction of application Serial No. 659,714. This object is attained by replacing the over-center arrangement of the parts as shown in application Serial No. 659,714 with an arrangement disclosed herein, one employing a hill and valley path for the link end 37, the path being such that link end 37 will move radially of the handle center 43 on breaker operation, as well as circularly, with the result that link end 37 will move away from abutment 29 a distance much greater than is the case when link end 37 can move circularly only, about center 43.

For an understanding of the breaker herein disclosed, reference is had to the following description and the accompanying drawings, in which

Figs. 1 and 2 are elevation and diagrammatic views, respectively, of the breaker in "on" position;

Figs. 3 and 4, respectively, show the parts in "off" and "overload off" positions.

The breaker includes a base 10 having a pair of contacts 11 which are to be engaged by the contacts 12 on the ends of a resilient bridging contact arm 13. One of the contacts 11 is connected to the line and the other is connected to one leg of the thermostatic or bimetallic warping element 14, the other leg of the latter being connected to the load. When the contact arm 13 is in "on" position, current flows through contacts 11 and 12, contact arm 13, and warping element 14.

To the vertically moving contact arm 13 is

rigidly secured an upwardly projecting sliding link 15 and a downwardly projecting guide plate 16, these being insulated from arm 13, as shown.

The lower end of the guide plate 16 slides between two spring jaws 17 of the lower guide block 18 firmly fastened to base 10. The sides of the sliding link 15 snugly fit into an upper guide block 19 rigidly secured to a vertical front plate 21.

A link 22 is pivotally connected at 23 to a horizontal link 24 and is also slidably connected to the upper end of the link 15 through an elongated slot 25 in link 15 receiving a pin 26 of link 22. A coil compression resisting spring 27 is mounted on the right hand end of link 24 between a pin 28 thereon and the bight of a U-shaped horizontally positioned spring compression link 29, which is pivotally connected at 31 to a pawl 32, the latter being pivotally connected by shouldered screws 33 on its left end to front plate 21. As indicated, the link 24 passes freely through a slot in the bight of link 29 and these links move as a unit around the pivot 31. In the "on" position the right hand or free end 35 of pawl 32 is held down by a tongue 36 of warping element 14.

The left hand end 37 of link 24 is pivotally connected to an operating bell crank 38 by a pin 39 sliding in a slot 41a of the crank. The bell crank has an extension 42 forming an operating handle for the device, and is pivotally supported on the cross shaft 43 mounted in the front plate 21.

The slot 41a, as contradistinguished from the corresponding slot 41 of the breaker of Serial No. 659,714, not only curves arcuately on pin 43 as a center, but is much wider than pin 39 so that it permits radial movement of pin 39 with respect to center 43. The front plate 21 is formed to provide a hill and valley edge whose valleys are numbered 21a and 21b and whose hill is numbered 21c, the edge forming a riding surface for the roller 39a on pin 39 of link end 37.

The parts just described may be operated as a simple, quick make and break switch as follows. Assume the parts to be in "on" position (Figs. 1-2). When the handle 42 is moved clockwise the bell crank 38 rotates clockwise carrying end 37 of link 24 along with it, thus moving links 24 and 29 together about pivot 31 clockwise. This action pulls link 24 to the left a slight degree and builds up an increased compression in coiled spring 27. All this while the link 22 and its pin 26 travel the length of the slot 25 in sliding link 15 and link 15 and arm 13 do not move, link 15 being held by the spring jaws 17 frictionally engaging guide part 16 while the lost motion con-

nection between the operating mechanism and the contact is taken up.

As soon as link 24 has passed over center (shaft 43), the coil spring 27 operates to move links 24 and 29 further past shaft 43 with a snap action, thus pulling contact arm 13 to its "off" position for quick break, slot 41a permitting snap action movement of links 24 and 29 independently of the handle 42 so that quick break may be effected 10 independently of and free of the operator.

Handle 42 is so connected that it may move the sliding link 15 without the assistance of the spring 27 after having taken up the lost motion provided in slots 25 and 41a. This permits the handle 42 15 to move the bridging arm 13 positively to the "off" position and permits the operator to free the contacts 12 in case they should stick and to move the switch positively to the "off" position, independently of the spring, in the event the 20 spring has become broken or weakened too much to function of its own accord.

The bell crank 38 may be moved to the extreme "off" position as limited by the engagement of the reset lug 44 and stop 45 on pawl 32.

25 Reverse movement of handle 42, to the left from the "off" position, Fig. 3, imparts a counter-clockwise movement to link 24 about pin 31 to pull link 24 to the left and compress spring 27 until link 24 is past center. All this while the 30 contact arm does not move. When link 24 passes over center, spring 27 expands to snap the parts, and the contact arm 13, to circuit closing position.

Slot 41a permits snap action movement of the 35 links 24 and 29 independent of the handle 42 so that quick make is independent and free of the operator. Positive make is assured by the positive connection between handle 42 and link 15 previously described.

During normal switch operation travel of pawl 40 32 about its pivot 33 is prevented by its end 35 being held by the anchorage tongue 36 of warping element 14.

For overload release warping element 14 will 45 release pawl end 35, permitting the compression in spring 27 to tend to move link 29, and consequently pin 31, to the left. Since link 29 is fixed to pawl 32 at 31 the movement of pin 31 to the left is necessarily accompanied by an upward movement of pin 31. The parts move up 50 until they assume the position of Fig. 4, which is the overload released position with contact arm 13 raised.

All this action is independent of the handle 42 and consequently assures a trip-free release of 55 the breaker.

For reset, handle 42 is rotated to the right to rotate link 24 clockwise around its pivot 31 and to cause reset lug 44 on the bell crank to engage a lug 45 on the pawl 32 and force the pawl down 60 until its end 35 hooks under the anchorage 36, link 24 meanwhile having its free end 37 elevated considerably above its normal closed position, with the result that when the reset is completed the parts are in the "off" position of Fig. 3. Contact arm 13 during such reset does not move towards its "on" position, and consequently the circuit is not closed during reset.

On switch operation, the degree of flexing of 65 spring 27 is responsive to the movement of pin 39 towards and from the spring abutment 29. In order to provide considerable flexure, it is necessary to provide considerable travel of pin 39 measured in a direction towards and away from the abutment 29. For this reason the slot 41a is made 70 considerably wide so that the pin 39 can move

radially of the handle center 43 as well as circularly about such center with the result that the movement of pin 39 during breaker operation and measured in a direction towards and away from the abutment 29 is considerably greater than 5 what would be the case if the slot 41a permitted circular movement only of pin 39 about center 43; and to insure pin 39 moving radially in the slot 41a and not hugging the edge thereof nearer the center 43, there is provided on the frame 21 the 10 hill and valley edge aforementioned, which edge defines the path of movement of the pin 39. The hill 21c is considerably more distant radially from center 43 than either of the valleys and consequently movement of the pin 39 from the lower 15 valley 21a towards and over the hill 21c provides a greater movement of the pin 39 from abutment 29 than would be the case if the path from valley 21a to hill 21c were truly circular with respect to the center 43. 20

I claim:

1. In a circuit breaker, an operating mechanism including a pivotally mounted link, and a link mounted to slide lengthwise through a part 25 of said first mentioned link and to move therewith about the pivot thereof, a coiled spring on the second link reacting between an abutment thereon and the aforementioned part of the first link, a bell crank pivotally mounted on its fixed pivot and having one branch formed to provide a handle and another branch pivotally connected to an end of the second link, and means causing such end to move radially of the bell crank pivot as well as circularly around the latter when the bell crank is rotated. 30

2. In a circuit breaker, an operating mechanism including a pivotally mounted link, and a link mounted to slide lengthwise through a part 40 of said first mentioned link and to move therewith about the pivot thereof, a coiled spring on the second link reacting between an abutment thereon and the aforementioned part of the first link, a bell crank pivotally mounted on its fixed pivot and having one branch formed to provide a handle and another branch pivotally connected 45 to an end of the second link, by a pin and slot connection whereof the slot is circular about the bell crank pivot and is wider than the pin riding therein, and means causing such end to move radially of the bell crank pivot as well as circularly around the latter when the bell crank is rotated. 50

3. In a circuit breaker, an operating mechanism including a pivotally mounted link, and a link mounted to slide lengthwise through a part 55 of said first mentioned link and to move therewith about the pivot thereof, a coiled spring on the second link reacting between an abutment thereon and the aforementioned part of the first link, a bell crank pivotally mounted on its fixed pivot and having one branch formed to provide a handle and another branch pivotally connected to an end of the second link, and means providing a hill and valley path whereof the hill is radially further from the bell crank pivot than the valleys for causing such end to move radially of the bell crank pivot as well as circularly around the latter when the bell crank is rotated. 60

4. In a circuit breaker, an operating mechanism 65 including a pivotally mounted link, and a link mounted to slide lengthwise through a part of said first mentioned link and to move therewith about the pivot thereof, a coiled spring on the second link reacting between an abutment thereon and the aforementioned part of the first link, a 70

75

- bell crank pivotally mounted on its fixed pivot and having one branch formed to provide a handle and another branch pivotally connected to an end of the second link, by a pin and slot connection 5 whereof the slot is circular about the bell crank pivot and is wider than the pin riding therein, and means providing a hill and valley path whereof the hill is radially further from the bell crank pivot than the valleys for causing such 10 end to move radially of the bell crank pivot as well as circularly around the latter when the bell crank is rotated.
5. In a circuit breaker, an operating mechanism including a pivotally mounted link, and a link 15 mounted to slide lengthwise through a part of said first mentioned link and to move therewith about the pivot thereof, a coiled spring on the second link reacting between an abutment thereon and the aforementioned part of the first link, 20 a bell crank pivotally mounted on its fixed pivot and having one branch formed to provide a handle and another branch pivotally connected to an end of the second link, and means formed from the fixed frame of the breaker which mounts the bell 25 crank pivot providing a hill and valley path whereof the hill is radially further from the bell crank pivot than the valleys for causing such end to move radially of the bell crank pivot as well as circularly around the latter when the bell crank 30 is rotated.
6. In a circuit breaker, an operating mechanism including a pivotally mounted link, and a link mounted to slide lengthwise through a part of said first mentioned link and to move therewith about 35 the pivot thereof, a coiled spring on the second link reacting between an abutment thereon and the aforementioned part of the first link, a bell crank pivotally mounted on its fixed pivot and having one branch formed to provide a handle and 40 another branch pivotally connected to an end of the second link, by a pin and slot connection whereof the slot is circular about the bell crank pivot and is wider than the pin riding therein, and means formed from the fixed frame of the breaker 45 which mounts the bell crank pivot providing a hill and valley path whereof the hill is radially further from the bell crank pivot than the valleys for causing such end to move radially of the bell crank pivot as well as circularly around the latter 50 when the bell crank is rotated.
7. In a circuit breaker, a frame, a pivotally mounted link, a pivotally mounted handle pivotally connected thereto and operable to slide the link circularly about the pivotal mounting of the 55 handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means for guiding the link, in its movement, so that it slides radially of the handle pivot when it is moved circularly about the handle pivot by the handle, the spring 60 being so positioned that it is stressed more by radial and circular movement of the link than by circular movement thereof alone.
8. In a circuit breaker, a frame, a pivotally mounted link, a pivotally mounted handle pivotally connected thereto and operable to slide the link circularly about the pivotal mounting of the handle, a contact controller connected to the link, 65 a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 70 being so positioned that it is stressed more by radial and circular movement of the link than by circular movement thereof alone.
9. In a circuit breaker, a frame, a pivotally mounted link, a pivotally mounted handle pivotally connected thereto and operable to slide the link circularly about the pivotal mounting of the handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 75 being so positioned that it is stressed more by radial and circular movement of the link than by circular movement thereof alone.
10. In a circuit breaker, a frame, a pivotally mounted link, a pivotally mounted handle pivotally connected thereto and operable to slide the link circularly about the pivotal mounting of the handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 80 being so positioned that it is stressed more by radial and circular movement of the link than by circular movement thereof alone.
11. In a circuit breaker, a frame, a pivotally mounted link, a pivotally mounted handle pivotally connected thereto and operable to slide the link circularly about the pivotal mounting of the handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 85 being so positioned that it is stressed more by radial and circular movement of the link than by circular movement thereof alone.
12. In a circuit breaker, a frame, a pivotally mounted link, a pivotally mounted handle pivotally connected thereto and operable to slide the link circularly about the pivotal mounting of the handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 90 being so positioned that it is stressed more by radial and circular movement of the link than by circular movement thereof alone.
13. In a circuit breaker, a frame, a pivotally mounted link, a pivotally mounted handle pivotally connected thereto and operable to slide the link circularly about the pivotal mounting of the handle, a contact controller connected to the link, a spring for opposing movement of the link out of one position and positioned to be stressed by and on movement of the link out of that position and to move the link with a snap action into another position when so stressed and when the link has been moved partially out of the first position and towards such other portion by the handle, and means on the frame for guiding the link, in its movement, so that it slides radially of the handle pivot when it is moved circularly about the handle pivot by the handle, the spring 95 being so positioned that it is stressed more by radial and circular movement of the link than by circular movement thereof alone.

dle is rotated to rotate the resilient mechanism about its latch connection end.

11. In a circuit breaker controlling mechanism, a resilient mechanism, a movable current responsive latch so constructed and arranged that it normally engages the mechanism for holding it, the parts being so arranged relatively that the mechanism, when held by the latch, is under longitudinal stress, the latch being movable on a circuit abnormality for releasing the mechanism, a rotatably mounted handle, means operatively connecting it to the mechanism, the handle being so constructed and arranged that on rotary movement thereof out of its normal position it will stress the mechanism longitudinally and move it bodily out of its normal position and towards the center of rotation of the handle so that when the handle is released after such movement the mechanism will tend to relieve itself of the longitudinal stress created therein by such movement of the handle with a snap action, the parts being so arranged relatively that on such stress relieving movement of the mechanism following such handle movement and sub-

sequent release, the mechanism will move bodily beyond the center of rotation of the handle and about the connection between the mechanism and latch as a pivot, and also being so arranged relatively that on release of the latch, when the handle and mechanism are in normal position, the mechanism will tend to relieve itself of the stress that it possesses when it is held by the latch with a snap action and in so doing will move bodily about its connection to the handle as a pivot, the resilient mechanism, the handle, and the latch being so arranged and constructed and relatively connected that the handle connection end of the resilient mechanism moves radially of the handle center of rotation a considerable extent as well as circularly thereof when the handle is rotated to rotate the resilient mechanism about its latch connection end, there being at the handle connection end of the resilient mechanism a hill and valley means providing a hill and valley path for the handle connection end of the spring means.

WILLIAM H. FRANK.
